Robert F. Beck

By *Robert F. Beck* Attorney

UNITED STATES PATENT OFFICE.

GEORGE F. ORMSBEE, OF SMITH CENTER, KANSAS, ASSIGNOR OF ONE-THIRD TO EARNEST JONES AND OF ONE-THIRD TO JESS MARTIN, BOTH OF SMITH CENTER, KANSAS.

WINDMILL.

Application filed April 21, 1923. Serial No. 633,697.

To all whom it may concern:

Be it known that I, GEORGE F. ORMSBEE, a citizen of the United States of America, and a resident of Smith Center, county of Smith, State of Kansas, have invented certain new and useful Improvements in and Relating to Windmills, of which the following is a specification.

This invention relates to certain improvements in windmills; and the nature and objects of the invention will be readily recognized and understood by those skilled in the arts involved in the light of the following explanation and detailed description of the accompanying drawings illustrating what I at present consider to be the preferred embodiments or mechanical expressions of the invention from among various other forms, arrangements, combinations and constructions of which the invention is capable within the spirit and scope thereof.

The present invention is particularly directed to the construction and arrangement of so-called windmill heads, and one of the main objects of the invention is to provide a windmill head with simple efficient mechanism for transmitting a maximum of power from the windwheel of the head, and further to so form and assemble the power transmitting mechanism that it may be readily and quickly removed for repairs or replacement.

A further object of the invention is to provide a windmill head with mechanism for transmitting power from the windwheel shaft of the head to a pump rod or similar element, in such a manner that the power is applied to the pump rod or other element at a minimum distance from the shaft center irrespective of the length of stroke of the pump rod.

A further object of the invention is to provide mechanism for transmitting power from a windwheel shaft of a windmill head to a pump rod or similar element, which permits of applying the power to the pump rod substantially in line with or longitudinally of its direction of movement, in order to reduce the application of lateral forces to the pump rod, with a resulting increase in power transmitted to the rod from the windwheel.

A further object of the invention is the provision of self-lubricating mechanism for

transmitting power from a windwheel, which mechanism is so formed as to maintain a sufficient supply of lubricant to efficiently lubricate the same over extended periods of time without inspection, adjustment or replenishment. 60

A further object of the invention is to provide a windmill head and power transmitting mechanism therefor, of few parts of simple construction which will be efficient in operation and durable in service, and further to so arrange and assemble the same as to permit of ready repair or replacement. 65

With the foregoing and various other objects in view, which other objects will be readily apparent to those familiar with this art, the invention consists in certain novel features in constructions and in arrangements and combinations of elements, as will be more fully and particularly pointed out 70 and referred to hereinafter.

Referring to the accompanying drawings, Fig. 1, is a view in elevation of a portion of a windmill head embodying the invention, parts thereof being shown in vertical section. 80

Fig. 2 is a view in side elevation of a portion of a windmill head of the invention. 85

Fig. 3, is a sectional view taken as along the line 3—3, of Fig. 1.

One form, arrangement and construction of a windmill head and power transmitting mechanism thereof embodying the features of the invention is illustrated in the accompanying drawings by way of an example for purposes of explanation of the principles of the invention. The tower or other support on which the windmill head is mounted is not shown, nor is the supporting and mounting bearing for the head shown, as it will be understood by and readily apparent to those familiar with this art that the illustrated windmill head can be mounted and supported in the usual, or any other desired manner. 90 95 100

In the present example and mechanical expressions of the principles of the invention, as shown in the drawings, the windmill head includes a main stem or extended sleeve 10 which is mounted and positioned in any suitable manner disposed vertically to form the axis around which the head is rotatable in operation of the windmill of which the head forms an element. A sub- 105 110

stantially flat oval-shaped casing 11 is fixed in vertical position on the main stem 10 in a vertical plane parallel with the axis of the stem but with the longitudinal axis of the casing inclined with respect to the axis of the stem. The main stem 10 is secured on and fixed to one side of the casing 11, and the opposite side of the casing is formed open and is closed by a removable side plate 12 secured to the casing through the medium of any suitable removable fastening means, such as the bolts or screws 14.

In the illustrated embodiment the casing 10 is formed of a casting with the main stem 10 integral therewith and projecting laterally from the closed side thereof, although it is not intended to limit the invention to such arrangement, as it will be clear that the casing and stem may be formed of separate elements and suitably secured together in desired position. The stem 10 extends downwardly any desired distance below the casing 11 and is provided with any suitable or desired bearing and mounting means (not shown) for rotatably supporting the windmill head on the desired tower or other support (not shown). The usual or any desired vane (not shown) for controlling the windmill head is suitably mounted on the casing 11, or other element of the head, as will be readily understood.

A supporting bracket 15, is in the present instance cast integral with the closed side of the casing 11 and extends outwardly therefrom on the opposite side of the main stem 10 from that toward and from which the upper portion of the casing is inclined (see Figs. 1 and 2). The upper end of the bracket 15, provides a horizontally disposed elongated pillow to receive the wheel shaft journal boxing 16. A windwheel shaft 17 is mounted in the journal boxing 16 and extends through the closed side of the casing 11, at which point suitable bearings 18 are provided. The outer end of the shaft 17 is provided with the usual windwheel 19, as diagrammatically indicated in the drawings. A pinion 20 is mounted on the inner end of the wheel shaft 17, within and enclosed by the casing 11 and side plate 12 thereof. A pump rod 21 is mounted in and extends through the main stem for reciprocation therein, in the usual manner. The upper end of the main stem above the casing 11 forms a guide 22 for the rod, which latter is provided with suitable slides or the like 23. The side of the guide 22 above the casing 11 is open to receive and permit operation of the pump rod 21 through suitable connections hereinafter described and explained.

The invention provides operating mechanism for actuating the pump rod 21 from the windwheel shaft 17 through the pinion 20

within the casing 11. This operating mechanism comprises a link 26 pivotally coupled to the pump rod 21 through a pin 27 secured on the pump rod and extending through the open side of the guide 22, and a pitman pivotally coupled to the link 26 and in operative connection with the windwheel shaft pinion 20 for actuation thereby to cause reciprocation of the pump rod through the link 26.

The pitman operatively connecting link 26 and pump rod 21 with the windwheel shaft comprises an elliptical or similarly shaped housing 24 formed with an open side and having an elliptical gear fixed centrally therein and spaced from the surrounding edge wall of the housing to provide a continuous unbroken passage or space surrounding and between the gear 25 and the edge wall of the housing. The elliptical gear 25 is formed of a thickness substantially equal to the depth or interior thickness of the housing 24, and is cut away on opposite sides thereof to form the opposite elliptical bearing surfaces or tracks 30 and 31 around the gear on opposite sides of the toothed portion thereof, as clearly shown in Figs. 2 and 3 of the drawings. An arm 28 extends from one end of the housing 24 centrally and in longitudinal continuation thereof. The upper end of the casing 11 is provided with an opening 29 therethrough, and the housing 24 of the pitman is loosely mounted and confined within the casing 11 with the arm 28 thereof extending through the opening 29 and pivotally coupled at its outer end with the link 26.

The housing 24 is mounted in operative position with its open side against and closed by the wall of the casing 11, and the pinion 20 of the shaft 17 fitting within the space between the elliptical gear 25 and the edge wall of the housing 24, with the pinion 20 spaced from said edge wall and in mesh with the elliptical gear 25. Bearing assemblies A and B, of the ball or other suitable anti-friction type, are mounted on the shaft 17 adjacent to and on opposite sides of the pinion 20, within the elliptical housing 24 (see particularly Fig. 3). Each of the bearing assemblies A and B includes an outer ring or cage 32 which is opposite the tracks 30 and 31, respectively, formed on the elliptical gear 25, and normally spaced from and out of engagement therewith. These rings 32 are so positioned, however, that they normally bear against and are in rolling engagement with the inner surface of the edge wall of housing 24, and thus function to maintain the pinion 20 in proper mesh with the elliptical gear 25 during operation of the windwheel shaft 17. The bearings A and B are further adapted to function as thrust bearings for the windwheel shaft 17. The housing 24 is main-

tained in the above described position in the casing 11 by the side plate 12, and the inner face or surface of the edge wall of casing 11 is formed of such a contour as to provide a bearing and guiding surface for the housing 24 throughout its cycle of movement, thereby maintaining the housing 24 in the casing 11 in proper position throughout the operation thereof.

10 Thus, from the foregoing, it is seen that upon rotation of the shaft 17 by the wind-wheel 19, the pinion 20 in mesh with the elliptical gear 25 is rotated and the gear 25 and housing 24 are reciprocated vertically 70 within the casing 11. The movement of the gear 25 and housing 24 is around the pinion 20 and bearing assemblies A and B, and the housing is maintained in the desired vertical position by the casing 11 against the inner 75 edge of which the housing 24 bears and is guided during its vertical reciprocation by and around the pinion 20. The mounting and position of the bearing assemblies A and B on the shaft 17, is such that, when 80 20 the pitman formed by the housing 24 and arm 28 reaches the limit or top portion of its stroke the tracks 30 and 31, engage the rings 32, respectively, of the bearings A and B, and prevent the pinion 20 and gear 25 85 25 from meshing too tightly and jamming. In this manner the bearings A and B in co-operation with the tracks 30 and 31 assist in maintaining the proper position of the pinion with the gear 25 throughout the 90 30 stroke of the pitman, and with a minimum of friction due to the rotational mounting 95 of the rings 32 of the bearings A and B.

10 The reciprocation of the housing 24, through rotation of the pinion 20 by the shaft 17 as above described, causes reciprocation and oscillation of the arm 28, which results in vertical reciprocation of the pump rod 21 through the link 26 which pivotally connects the arm 28 with the pump rod. By 105 15 the construction and arrangement described, it will be noted that the power is transmitted from the windwheel shaft to the elliptical gear of the pitman at a minimum distance from the center of the windwheel shaft, thus reducing torque and strains on the shaft and the pitman to a minimum. Further, the length of stroke of the pitman and the pump rod can be increased without 110 20 increasing the distance from the shaft at which the power is applied, as the length of the elliptical gear is increased, with corresponding increases in cooperating elements without increasing the distance from the pinion at which the power is applied to the pitman.

25 The compact assembly and mounting of the casing and power transmitting mechanism on the main stem, and the position thereof with respect to the pump rod, permits the application of the power or lift

to the pump rod substantially longitudinally of or along its direction of movement. This reduces lateral application of forces to the pump rod and substantially increases the power applied, by reducing losses in power 70 from friction on the pump rod and from the application of forces against the direction of movement of the rod. In the illustrated example, the power is applied to the pump rod by the pitman in practically a direct 75 line with the vertical movement of the rod, as will be clear by reference to the accompanying drawings.

In order to provide for the proper and efficient lubrication of the housing 24 and 80 gears 25 and 20, the casing 11 is formed as a lubricant reservoir capable of holding and maintaining a supply of lubricant sufficient for extended periods of time. The removable side plate 12 is formed to provide a leak proof closure for the casing 11, and a body or supply of lubricant is placed therein through the opening 29 in which the arm 28 operates. After a sufficient quantity of lubricant is placed in the casing, during 85 90 operation of the windmill head the housing 24 will work therein and lubricant will be continuously supplied to the interior of the housing to lubricate the elliptical gear 25 and the pinion 20, as well as to the outside 95 of the housing to lubricate those surfaces thereof in contact with the casing 11. Once a supply of lubricant is placed in the casing 11, the windmill head can be operated for an extended period of time without attention or replenishment of lubricant.

100 Removal of the housing 24 is readily accomplished by removing the side plate 12 of the casing 11 and slipping the housing from position. This permits of repair and replacement without the necessity of completely disassembling the windmill head.

105 Although the invention is illustrated and described as embodied in a windmill head, various features thereof are applicable 110 mechanisms for the transmission of power and other embodiments where similar or equivalent conditions are encountered.

115 It is evident that various changes, variations, substitutions and departures might be resorted to without departing from the spirit and scope of the invention, and hence I do not wish to limit myself to the exact disclosures hereof.

120 Desiring to protect my invention in the broadest manner legally possible, what I claim is:

1. In a windmill head, a main stem, a vertically disposed casing mounted on said main stem, a windwheel shaft extending into said casing, a pinion mounted on said shaft within said casing, a pitman extending into said casing and embodying a housing within the casing formed with an elliptical gear 125 130 therein in mesh with said pinion within the

casing, the inner edge face of said casing forming a bearing and guiding surface for said pitman during reciprocation thereof by said pinion.

- 5 2. In a windmill head, a main stem, a substantially flat casing mounted in vertically disposed position on said main stem, a pump rod mounted in and extending through said main stem, a windwheel shaft 10 extending into said casing, a pinion mounted on said shaft within the casing, a pitman extending into said casing and formed of a substantially flat elliptical housing having an open side, an elliptical gear mounted 15 centrally of and spaced from the edge wall of said housing, and an arm forming a longitudinal continuation of said housing, the said pitman mounted in said casing with the open side thereof closed by a side wall of 20 the casing, and the wheel shaft pinion fitting into the space around and in mesh with the elliptical gear, the said arm of the pitman extending upwardly through the edge wall of the casing, operative connections from 25 said arm to the pump rod, and the inner edge wall of said casing forming a bearing and guiding surface for said housing to maintain the pitman in proper position during operation thereof.

- 30 3. In a windmill head, a windwheel shaft,

a pinion mounted thereon, roller bearing members mounted on said shaft at opposite sides of said pinion, a pitman formed by a substantially elliptical shaped housing, an elliptical gear mounted in said housing, and 35 spaced from the edge wall thereof, and said pinion in mesh with said elliptical gear with said roller bearing members in engagement with the edge wall of said pitman housing to form guide members maintaining said 40 gear and pinion in mesh.

4. In a windmill head, a wind wheel shaft, a pinion fixed thereon, roller bearing members mounted and rotatable independently of said shaft at opposite sides of said pinion, a pitman formed by a substantially flat housing, an elliptical gear mounted in said housing and spaced from the edge wall thereof, said pinion in mesh with said gear with said roller members normally bearing 45 against the edge wall of said housing, and said elliptical gear provided with tracks therearound alined with said roller members, respectively, and adapted to be engaged thereby to maintain said pinion in 50 proper mesh with the said gear.

Signed at Smith Center, Kansas, this 3d day of Mar., 1923.

GEORGE F. ORMSBEE.
